UNITED STATES PATENT OFFICE.

EUGENE M. MIX AND JAMES E. MIX, OF BUFFALO, NEW YORK, ASSIGNEES
TO THE CLARK MANUFACTURING COMPANY, OF SAME PLACE.

KNOB ATTACHMENT.

SPECIFICATION forming part of Letters Patent No. 247,940, dated October 4, 1881.

Application filed August 1, 1881. (Model.)

To all whom it may concern:

Be it known that we, EUGENE M. MIX and JAMES E. MIX, citizens of the United States, residing at Buffalo, in the county of Erie and State of New York, have invented new and useful Improvements in Door-Knobs, of which the following is a specification.

This invention relates to certain improvements in door and other knobs; and it has for its objects to provide a means for securing a knob of any suitable material to a metallic shank in such manner as to prevent any possibility of its working loose from said shank, and at the same time form a connection that will give the utmost solidity and a highly-ornamental appearance to the knob.

To this end our invention consists of a knob constructed of any suitable material, and provided with an aperture extending entirely through it, in combination with a metallic shank having a flange or shoulder adapted to bear against the rear of the knob, and a cylindrical or slightly-tapering extension adapted to fit in the aperture in the knob and extend nearly through it, the said extension being provided with longitudinal wings or feathers on the outside adapted to fit in corresponding grooves formed in the walls of the aperture in the knob, to prevent the same from turning, and with an interior female screw for the reception of a plain headed screw, which may be inserted from the outside, the head of said screw being adapted to bear against the outside of the knob, and the inner end being slotted, whereby it can be turned to clamp the parts together, as more fully hereinafter specified.

In the drawings, Figure 1 represents a longitudinal sectional view, showing two of our improved knobs secured to the shanks and the connecting-spindle. Fig. 2 represents a detached view of the knob. Fig. 3 represents a sectional view of the knob detached from the shank, showing the central aperture and grooves for the reception of the wings or feathers. Fig. 4 represents a rear view of the shank; Fig. 5, a longitudinal section of the same; Fig. 6, a front view of said shank; and

Fig. 7, a sectional view of the shank and knob, showing the means of securing the knob to the shank.

The letter A indicates the knob, which may be constructed of any suitable shape or design, and of any desired material. The said knob is provided with a central aperture, B, extending entirely through it, which aperture may be of cylindrical or other form, and may taper slightly from the rear to the front of the knob. The said aperture, when cylindrical in shape, is provided with one or more grooves, C, two diametrically opposite each other being represented in the present instance.

The letter D indicates the metallic shank. This is hollow throughout, as shown in detail in Fig. 5, and is internally squared at its rear for the reception of the spindle E, which is rectangular in cross-section. The said shank is provided externally with a flange or shoulder, F, and with an extension, G, which may be either of cylindrical or other shape to correspond with the shape of the aperture in the door-knob. The said extension may be made slightly tapering, and when of cylindrical shape is provided with one or more wings or feathers, H, which fit in the groove or grooves in the aperture in the door-knob, and prevent the knob from turning upon the shank. The extension is provided with an internal female screw, I, which may either be formed directly in the body of the shank or may be formed in a bushing, K, of softer metal, secured in said shank, as shown in Fig. 5, and scored longitudinally, as shown, to enable the clamping-screw L to take better hold.

The letter E indicates the clamping-screw. This is formed with a head, N, which is adapted to bear against the outer face of the knob. The said screw at its smaller end is slotted, as indicated by the letter P, by means of which it can be turned by a screw-driver or key inserted through the rear end of the shank, so as to bind all the parts securely together, as clearly indicated in Fig. 7 of the drawings.

As constructed, it will be perceived that there are no parts that will be apt to work loose, as the shank has a positive bearing in-

side and outside at the rear of the knob, while the binding-screw has a positive bearing against the outside, the said screw, besides forming a solid and secure connection, forming a highly ornamental appendage to the knob. Moreover, as the screw is slotted on its inner instead of its outer end, it is impossible to remove the knob from the shank from the outside without the use of special tools, thus securing all the advantages of a knob having the shank secured to an inside connection, and a knob screwed to the shank from the outside, and obviating the objections attendant upon both of such styles of knobs.

15 What we claim, and desire to secure by Letters Patent, is— The metallic shank provided with a shoulder or flange adapted to bear against the rear

of a knob, and provided with an extension ~~adapted~~ ²⁰ adapted to pass nearly through an opening in the knob, the said extension having one or more wings or feathers adapted to set in grooves in the knob, and a headed screw slotted at its inner end and adapted to fit in the screw-threaded portion of the shank, and to be turned ²⁵ from the inside to clamp the knob on the shank, substantially as and for the purpose specified.

In testimony whereof we have hereunto set our hands in the presence of two subscribing witnesses.

EUGENE M. MIX.
JAMES E. MIX.
